(57) **CLAIM**

We claim the ornamental design for a connector, as shown and described.

DESCRIPTION

FIG. 1 is a perspective view of a connector in accordance with our new design;

FIG. 2 is a front elevation view thereof, the rear elevation view being identical;

FIG. 3 is a right side elevation view thereof, the left side elevation view being identical;

FIG. 4 is a top plan view thereof;

FIG. 5 is a bottom plan view thereof; and,

FIG. 6 is a cross-sectional view illustrating the profile taken through line 6-6 as shown in FIG. 2.
